(57) **CLAIM**

The ornamental design for a bus bar carrier for a lithium ion battery module, as shown and described.

DESCRIPTION

FIG. 1 is an overhead perspective view of the bus bar carrier for a lithium ion battery module showing our new design; FIG. 2 is a underside perspective view thereof; FIG. 3 is an overhead plan view thereof; FIG. 4 is a bottom plan view thereof; FIG. 5 is a right side elevation view thereof, the left side being a mirror image; FIG. 6 is a front elevational view thereof; and, FIG. 7 is rear elevational view thereof.
